ENGINE PREHEATER

Bernard H. Pickard, Toronto, Ontario, Canada, assignor
to Bardon Research and Development Limited,
Toronto, Ontario, Canada

Filed July 6, 1971, Ser. No. 160,269

Term of patent 14 years

Int. Cl. D23—03

U.S. Cl. D23—86

FIG. 1

FIG. 2

FIG. 3

FIG. 1 is a perspective view of an engine preheater showing my new design.

FIG. 2 is a rear view of the engine preheater illustrated in FIG. 1, and

FIG. 3 is an end view of the engine preheater illustrated in FIG. 1.

The four ribs shown in FIG. 3 that project into the circular passage extending through the engine preheater extend for about the length of and are positioned adjacent to the enlarged intermediate section of the engine preheater.

I claim:

The ornamental design for an engine preheater, as shown and described.
